UNITED STATES PATENT OFFICE.

FREDERICK COATES, OF CINCINNATI, OHIO, ASSIGNOR TO FEDERAL PRODUCTS COMPANY, OF CINCINNATI, OHIO, A CORPORATION OF OHIO.

AUTOMATIC CARTON-HEADING MACHINE.

Application filed August 11, 1921. Serial No. 491,450.

To all whom it may concern:

Be it known that FREDERICK COATES, a citizen of the United States, residing at Cincinnati, in the county of Hamilton and 5 State of Ohio, has invented certain new and useful Improvements in Automatic Carton-Heading Machines, of which the following is a specification.

This invention relates to paper or pulp 10 can manufacturing machinery of the class used for heading paper and other like containers.

The invention more particularly relates 15 to a can capping or heading machine forming an improvement over my prior application filed the 27th day of April 1921 and bearing the Serial Number 464,832.

More particularly the invention consists 20 in a continuously operating automatic machine for applying the heads to paper or pulp cans.

With the above and other objects in view, the invention consists in general of certain 25 novel details of construction and combinations of parts hereinafter fully described, illustrated in the accompanying drawings, and specifically claimed.

In the accompanying drawings, like characters of reference indicate like parts in 30 the several views, and:—

Figure 1 is a side elevation partly in section of a machine constructed in accordance with this invention.

Figure 2 is a plan view thereof on a reduced scale.

Figure 3 is a detail section partly in elevation, on the line 3—3 of Figure 2.

Figure 4 is a detail section partly in elevation, on the line 4—4 of Figure 2.

40 In the embodiment of the invention herein illustrated there is disclosed a base 10 and extending upward from this base are standards or posts 11. On the upper ends of these posts is supported a frame 12 one 45 part of which consists of a ring and to the under side of this ring is secured a cam ring 13 carrying a cam rib 14.

Extending centrally of the machine is a vertical shaft 15 which is journaled in 50 the base 10 and in a boss 16 depending from the upper frame 12. On the lower end of this shaft is fixed a worm wheel 17 wherewith meshes a worm 18 carried on the shaft 19 driven by any suitable means, 55 not shown. Also on the shaft 15 is mount-

ed a two armed spider having a hub 20 fixed to the shaft as by a set screw 21 or any other suitable means. Extending from this hub 20 are the arms 22 of said spider and these arms are positioned diametrically 60 opposite each other and terminate at their outer ends in vertical elongated heads 23. On each of these heads is supported a bracket consisting of a vertical portion 24, an upper leg 25, and a lower leg 26. The 65 upper and lower legs extend outward and are provided with aligned bearing bosses 27. In the lower of these bearing bosses is fitted a shaft 28 supporting a can carrier 70 consisting of a base 29 from the inner side of which extends upward an arcuate wall 30 extending 180° around said base. Carried in the outer end of the leg 26 is a pivot pin 31 whereon is mounted a hub 32 having a forwardly extending arm 33 carrying 75 a semi-circular closure wall 34, these parts being so positioned and arranged that the walls 30 and 34 may be brought together to form a cylindrical box or casing open 80 at the top. As will be seen from the right of Figure 1 this casing is completed while the arm 33 is in a vertical position. Extending laterally from the boss or hub 32 is a trip arm 35. At 36 is a standard carrying an inclined cam 37 which is arranged 85 in the path of the trip arm 35 so that as the spider revolves the cam 37 will engage the top of the trip arm 35 and throw the same downward thus opening the cam receptacle and exposing the can C as shown 90 at the left of Figure 1. A second standard 38 is also provided carrying an inclined cam 39 against which the under side of the trip arm 35 engages when thrown open. Thus during the revolution of the spider 95 each of the can holders is opened by the action of the cam 37 so that a can C may be placed in or removed from the holder. Slidable in the bearings 27 are plungers 40 which are forked at their upper ends and 100 carry cam rollers 41 which bear against the cam rib 14. These rollers are held against said rib by means of suitable springs 42 and on the lower ends of the shafts 40 are supported can closing heads each of these heads 105 consisting of a body portion 43 having a frusto-conical recess 44 in its lower surface wherein is seated a series of frusto-conical ring segments 45 each of which is grooved as at 46 on its inner surface to receive the 110

rib 47 of a disk 48 slideable on the shaft 40. It will be noted that the head 43 is held on the shaft by a set screw 49. Extending through the head or body 43 are stop pins 50 which are screwed into the disk 48 and on these stop pins between the top of the recess 44 and the disk 48 are springs 51 which normally hold the disk pressed downward as shown in Figure 4.

10 As will be seen from Figures 3 and 4 the can C is provided with a head H and the action of the can closing head is such as to crimp the flange F of the head H down on the side walls of the can C.

15 In the operation of the device the operator places a top or head on a can and positions the same in the carrier. At this time the outer wall of the carrier is open and the closing head is raised. As the spider moves 20 around the rib 14 acts on the rollers 41 to force the closing head down and this head is held down until the carrier again reaches the operator's position. Just prior to reaching the operator's position the front wall 34 25 is thrown open by the cam 37 so that the operator can now remove the sealed and closed can and replace the same with one ready for sealing. Thus all the operator has to do is to change the cans in the carriers.

30 There has thus been provided a simple and efficient device of the kind described and for the purpose specified.

It is obvious that minor changes may be made in the form and construction of the 35 invention without departing from the material principles thereof. It is not therefore desired to confine the invention to the exact form herein shown and described, but it is wished to include all such as properly come 40 within the scope claimed.

Having thus described the invention, what is claimed as new, is:—

1. In a carton heading machine, a carton carrier having a base to support a carton, a 45 fixed side to engage one side of the carton, and a movable side hinged to swing to and from the fixed side, means to move the carrier continuously around a circular path, a

lug projecting from the movable side, a fixed cam in the path of said lug arranged 50 to engage the lug and move the movable side away from the fixed side, and a second cam in the path of the lug arranged to engage the lug and move the movable side towards the fixed side.

55

2. In a carton heading machine, a carton carrier having a side movable to open and closed positions, means to move the carrier along a definite path, means adjacent said path to effect opening and closing of said side, a heading die above the carrier and movable therewith, means to depress said die while the movable side is closed, and means to raise the die while the movable side is open.

60

3. In a carton heading machine, a carton carrier having a base to support a carton, a fixed side to engage one side of the carton, and a movable side hinged to swing to and from the fixed side, means to move the carrier along a definite path, means adjacent said path to effect swinging of the movable side towards and from the fixed side, a heading die above the carrier and movable therewith, means to depress said die while the movable side is closed, and means to raise the die while the movable side is open.

70

4. In a carton heading machine, a carton carrier having a base to support a carton, a fixed side to engage one side of the carton, 80 and a movable side hinged to swing to and from the fixed side, means to move the carrier along a definite path, a lug projecting from the movable side, a fixed cam in the path of said lug arranged to engage the lug 85 and move the movable side away from the fixed side, a second cam in the path of the lug arranged to engage the lug and move the movable side towards the fixed side, a heading die above the carrier and movable therewith, means to depress said die while the movable side is closed, and means to raise the die while the movable side is open.

75

In testimony whereof I affix my signature.

FREDERICK COATES.
